UNITED STATES PATENT OFFICE.

BARTON M. JONES, OF PIQUA, OHIO.

HYDRAULIC TRANSPORTATION SYSTEM.

1,419,143.

Specification of Letters Patent. Patented June 13, 1922.

Application filed August 19, 1921. Serial No. 493,648.

To all whom it may concern:

Be it known that I, BARTON M. JONES, a citizen of the United States, residing at Piqua, in the county of Miami and State of Ohio, have invented certain new and useful Improvements in Hydraulic Transportation Systems, of which the following is a specification.

This invention relates to hydraulic sluicing and transporting systems for ashes, manufacturing refuse, clay, sand, gravel, rock, ore and other solid substances, and its primary object is to provide a simple, practical and highly efficient method of giving a uniform transporting capacity to every part of a sluiceway or other conduit, irrespective of differences in their grades, cross-sectional dimensions or roughness.

I attain this object by continuously circulating through a part of a sluiceway or other conduit of lesser transporting capacity than a preceding or following part, a quantity of water which with the normal flow through the other parts is sufficient to carry the material through said part at a rate equal to that of the full capacity of any other part.

My invention is particularly adapted for use in hydraulic transportation systems wherein the transporting capacity of any part is limited by natural topographical conditions, cost of material, or other circumstances, and it provides an economical method of remedying a condition which ordinarily would necessitate a reduction in the rate of feed below the capacity of the pump or other contrivance provided to convey material to a point of delivery.

In the accompanying drawings in the various views of which like parts are similarly designated;

Figure 1 represents a sectional elevation of a hydraulic conveying system to which my invention is applied;

Figure 2, a similar elevation showing a different arrangement of the parts of the system, and

Figure 3, a plan view of a sluiceway showing still another condition which would render the use of my invention desirable.

Figure 1 of the drawings shows a hydraulic sluicing or transporting system for ashes, manufacturing refuse, clay, sand, gravel, rock, ore and other solid substances, including a sluiceway 5, which is inclined 5 from an elevated point of supply A to a sump or reservoir 6, from where the mate-

rial is conveyed to a point of delivery through the instrumentality of a pump 7.

To illustrate the use and advantages of my invention I have shown the sluiceway to be composed of two parts one of which, from C to D, has lesser hydraulic gradient or slope than the preceding part from A to C, and a lesser transporting capacity than either the part A to C or the part D to O. 65

It is obvious that the transporting capacity of the entire system is limited to that of the part C—D, and to remedy this limitation, a supplementary quantity of water is supplied at the upper end of said part sufficient to compensate for the difference in its inclination with relation to the preceding part or its transporting capacity with relation to the parts between which it is disposed. 75

The water supplied at the upper end of the part C—D of the sluiceway is drawn off at the opposite end of the same, after it has performed its function of increasing the transporting capacity of said part, and under conditions where a scarcity of water necessitates an economical use thereof, some or all of this water may be returned by means of a pump 9 to the upper end of the part C—D of the sluiceway to repeatedly perform its function in a continuous circulatory movement. 85

In the illustration shown in the drawings, the water is supplied to the upper end of the part C—D from a reservoir 8 through the medium of the pump 9 and a conduit 12 and is withdrawn at the lower end of the part through an overflow 10 from where it is conveyed to the pump 9 by a pipe 13. 90

In Figure 2 of the drawings I have shown the sluiceway as having a part E—F of closed conduit following a part F—G of lesser transporting capacity. The method of applying my invention is similar to that herein described with relation to the construction shown in Figure 1. 95

Figure 3 illustrates a sluiceway in which a part H—K has a lesser transporting capacity than the preceding part K—L by reason of a difference in their cross-sectional form. 105

The application of my invention to a sluiceway of this character is similar to the method illustrated in Figures 1 and 2 and needs no further illustration or explanation. 110

Having thus shown and described the application of my improvements by the

simplest and most feasible methods at present known to me, I desire it understood that variations in the arrangement of the parts may be resorted to without departing 5 from the spirit of my invention.

It has been indicated hereinbefore that in places where a plentiful supply of water is available, the pump for returning of water for reuse through the retarding section of 10 the sluiceway may be eliminated, and it will be apparent that my improvements are applicable to closed conduits as well as to open sluiceways, and under conditions different from those shown in the drawings 15 and hereinbefore described, which necessitate an acceleration of the flow of material through any part of a hydraulic system for the conveyance of solid substances separate from the other parts thereof.

Having thus described my invention, what 20 I claim and desire to secure by Letters-Patent is:

1. In a hydraulic transportation system having in a sluiceway or conduit, a part of 25 lesser transporting capacity than another part thereof, means for continuously circulating a supplementary quantity of water through the part first mentioned for the purpose of increasing its transporting capacity, exclusive of said other part.

2. In a hydraulic transportation system having in a sluiceway or conduit, a part of 30 lesser inclination than another part thereof, means for continuously circulating a supplementary quantity of water through the part first-mentioned for the purpose of increasing

its transporting capacity, exclusive of said other part.

3. In a hydraulic transportation system having in a sluiceway or conduit, a part of 40 lesser transporting capacity than another part thereof, means for supplying supplementary water at one end of the part first mentioned for the purpose of increasing its transporting capacity and withdrawing this 45 water at the other end of the same.

4. In a hydraulic transportation system having in a sluice-way or conduit, a part of 50 lesser transporting capacity than an other part thereof, a source of water supply, a pump for conveying water from said source to an end of the part first mentioned, and an overflow weir for returning said water to said source from the other end of the same.

5. The method of equalizing the transporting capacity of a sluiceway or conduit having a part of lesser transporting capacity than another part, consisting in continuously 55 circulating a supplementary quantity of water through the part first mentioned, exclusive of said other part.

6. The method of equalizing the transporting capacity of a sluiceway or conduit having a part of lesser transporting capacity than another part, consisting of supplying 60 supplementary water at an end of the part first mentioned and withdrawing it at the opposite end of the same.

In testimony whereof I have affixed my signature.

BARTON M. JONES.
